UNITED STATES PATENT OFFICE.

CLARENCE E. ELLIOTT AND ORVILLE O. NICHOLS, OF KANSAS CITY, MISSOURI.

DESIGN FOR AN ORNAMENT FOR A RADIATOR-CAP.

58,899.

Specification for Design.

Patented Sept. 6, 1921.

Application filed June 20, 1921. Serial No. 479,132. Term of patent 3½ years.

To all whom it may concern:

Be it known that we, CLARENCE E. ELLIOTT and ORVILLE O. NICHOLS, citizens of the United States, residing at Kansas City, in the county of Jackson and State of Missouri, have invented a new, original and ornamental Design for Ornaments for Radiator-Caps, of which the following is a specification, reference being had to the accompanying drawing, forming part thereof, in which—

Figure 1 is a plan view of our new design.
Fig. 2 is a side elevation of the design.

We claim:

The ornamental design for an ornament for a radiator cap, as shown.

CLARENCE E. ELLIOTT.
ORVILLE O. NICHOLS.
